UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

ENVELOP-MACHINE.

1,282,314.

Specification of Letters Patent. Patented Oct. 22, 1918.

Application filed February 17, 1916. Serial No. 79,002.

To all whom it may concern:

Be it known that I, WILLARD E. SWIFT, a citizen of the United States, residing at Worcester, in the county of Worcester and 5 Commonwealth of Massachusetts, have invented a new and useful Improvement in an Envelop-Machine, of which the following, together with the accompanying drawings, is a specification.

My present invention relates to an envelop machine for making what are known as window envelopes, or envelopes having an opening covered by a transparent patch for the purpose of disclosing an address on the inclosure, and it relates particularly to the mechanism for applying a patch to cover the opening in an envelop blank. The mechanism by which this result is accomplished is herein described and illustrated in the accompanying drawings, the novel features being pointed out in the claims appended hereto.

Referring to the accompanying drawings, Figure 1 is a side view of so much of an envelop machine as is necessary to illustrate the nature of my present invention.

Fig. 2 is a plan view of the patch applying mechanism.

Fig. 3 is a side view of the patch applying mechanism, shown in section and upon a larger scale.

Fig. 4 is an elevation of the roller for applying gum to the transparent patch.

Fig. 5 is an elevation of the guideway 35 through which the gummed patch is conducted to the patch applying mechanism.

Fig. 6 represents a blank having an opening therein covered by a transparent patch, the blank being shown in its extended form 40 preparatory to the operation of folding.

Similar reference characters refer to similar parts in the different figures.

Referring to Fig. 1, 1 denotes the framework of an envelop machine, 2 denotes a 45 table for supporting a stack 3 of envelop blanks, said table having an upward movement as the blanks are being removed therefrom by the operation of the machine, for the purpose of maintaining the topmost 50 blank in substantially the same horizontal plane. The table moving mechanism, however, is not shown as it is a common device in envelop machines of this class and its operation will be well understood. In the operation 55 of the ordinary envelop machine em-

ploying a feed table 2, the flaps of the blank are gummed while they rest upon the feed table and the blanks are then transferred by a reciprocating carriage to the folding mechanism.

In my improved machine I employ the feed table 2 for supporting a pile of blanks having an opening 4 in the body portion of the envelop blank, as shown in Fig. 6, to which I apply a transparent patch 5 to 60 cover the opening 4 in the blank 6 by means of a patch applying mechanism, as shown in sectional view in Fig. 3. The material from which the transparent patches are formed is supported in the form of a coil or roll 7 upon 65 an arbor 8 journaled in the framework of the machine. From the coil 7 the strip 9 of transparent material, having a width equal to the desired length of the patch, is conducted beneath a floating roll 10, capable of 70 a rising and falling motion within a slot 11, in order to take up any slack in the strip 9, thence over a roll 12 journaled in fixed bearings in the framework of the machine and between the rolls 13 and 14. The roll 13 is 75 intermittently rotated by a pawl and ratchet mechanism 15, Fig. 2, said pawl and ratchet mechanism being actuated by a suitable cam through a push rod 16. The transparent strip 9 is pinched between the roll 13 and the 80 raised ends 17, 17 of the roll 14. At each intermittent movement of the roll 13, a sufficient length of the transparent strip is withdrawn from the roll 7 to form one of the 85 patches to be applied to the envelop blank. 90

The roll 14 is provided on its periphery with gumming dies 18, divided by gaps 19, in order to interrupt the line of gum applied to the strip 9 by the gumming dies. 95 The gumming dies 18 are arranged to apply broken lines of gum to the strip 9 in a contour corresponding to the margin around the opening 4 in the envelop blank, the spaces corresponding to the gaps 19 being ungummed. Gum is supplied to the dies 18 from a gumming roller 20, rotating in contact with a body of gum 21 held in a gum pan or box 22, the gum being transferred from the roller 20 to the gumming dies by an intermediate roller 23. 100

The transparent strip 9 as it leaves the rolls 13 and 14 is projected through a guideway 24, and, in its passage through the guideway 24, it is supported by the ribs 25 which contact with that portion of the strip 110

left ungummed by the gaps 19. From the guideway 24 the gummed strip 9 is projected forward beneath a vertically reciprocating presser foot 26, which carries a knife 5 blade 27 coöoperating with the edge 28 of the guideway 24 to sever the transparent strip during the downward movement of the presser foot 26. An air passage 29 has an open end at the presser foot and communicates through a flexible pipe 30 with an air pump, not shown, which serves at the proper moment to exhaust air from the passage 29 and cause the adhesion of the projected end of the transparent strip to the presser foot. 10 The downward movement of the presser foot 26 cuts off a patch from the transparent strip, which is held upon the presser foot by suction until it is carried down into contact with the topmost blank in the stack 3. 15 The presser foot slides in fixed ways in the framework of the machine and the stack 3 of blanks is maintained by the gage pins 31, with the opening 4 in the blank in registration with the descending patch held upon 20 the presser foot 26.

As the patch is applied to the topmost blank in the stack, the valve stem 32 contacts with the stop 33 and is forced upwardly against the tension of a spiral spring 34 30 to lift the valve 35 from its seat, to close the pipe 30 and admit air through the opening 36 to the air passage 29, thereby releasing the patch which adheres to the envelop blank as the presser foot 26 rises. The presser foot 26 is provided with an arm 37 which carries a suction tube 38 connected by a flexible pipe 39 with an air pump, not shown. The downward movement of the presser foot 26 carries the tube 38 into contact with the topmost blank of the stack 3 and, at that moment, air is exhausted from the suction tube 38, causing the topmost blank to be lifted by one edge from the stack 3. As the suction tube 38 rises, a 40 valve 40 is pushed in by its contact with the inclined surface 41 against the tension of a spiral spring 42, thereby closing the communication between the tube 38 and the flexible pipe 39 and connecting the tube 38 with an air opening 43, which causes the release of the raised envelop blank. 45

While one edge of the topmost blank is held in its raised position by the suction tube 38, a reciprocating carriage 44, Fig. 1, slides 55 between the raised blank and the stack 3, actuated by an eccentric 45 through the swinging lever 46 and link 47. The carriage 44 carries a gripper 48 which seizes the raised envelop blank and, on its rearward motion, draws it beneath retaining pawls 49 where it is engaged by hooks 50 and moved rearward at the next reciprocation of the carriage beneath the retaining pawls 51, where it rests upon a table 52 during the 60 next forward movement of the carriage 44.

At the next rearward movement of the carriage, the blank is pushed forward by hooks 52^a upon a creasing table 53 and beneath a vertically reciprocating plunger 54, which pushes the blank through a rectangular opening in the creasing table upon the folding bed, where its flaps are folded by hinged folders 55. 70

The mechanism for transferring the blank from the stack 3 to the creasing table 53 is 75 copied from the envelop machine for which Letters Patent were granted to A. A. Rheutan April 16, 1889, No. 401,462. The detail mechanism for operating the reciprocating carriage 44 and gripper 48 is not herein 80 shown nor described as it forms no part of my present invention and is clearly set forth in the aforesaid patent to Rheutan. In my improved machine, however, I provide a table 52 for supporting the envelop blank 85 while it is retained by the pawls 51 and, during the dwell of the blank upon the table 52, I apply gum to the flaps of the envelop by means of gumming dies 56 and 57 which are carried upon a vertically reciprocating 90 spindle 58. The gumming dies 56 and 57 are supplied with gum by a traversing gumming roll receiving gum at one end of its movement from a gum roll running in a gum box 59, in the usual manner in machines of 95 this class.

It has been proposed in the manufacture of window envelops to apply a patch to cover the opening in the blank between the operations of gumming the flaps of the 100 envelop and folding the blank. Difficulty is frequently experienced in first gumming the flaps of the blank and subsequently subjecting the gummed blank to the mechanical operations necessary in applying a patch to 105 cover the opening and in folding the flaps of the blank to form a completed envelop.

It is one of the objects of my present improvement to complete the operation for which gum has been applied as soon after 110 the application of gum to the envelop blank as possible, and in the operation of my improved machine forming the subject of this application, I first apply adhesive material to affix the transparent patch to the blank 115 and as soon as possible thereafter I apply the patch to cover the opening. The blank, with no gummed surface exposed, is then transferred to the flap gumming mechanism and, immediately thereafter, the blank by 120 its next movement is carried upon the creasing table and subjected to the action of the plunger 54 and the hinged flap folders 55.

I claim,

1. In an envelop machine, the combination of the following instrumentalities arranged for conjoint action in the order named, means for applying gum to a patch, means for applying the gummed patch to cover an opening in an envelop blank, means 130

- for applying adhesive material to the flaps of the blank, and means for folding the blank.
2. In an envelop machine, means for supporting a pile of envelop blanks having openings therein, means for applying a patch to cover the opening in the topmost blank of said pile, mechanism for gumming the flaps of the blank, a folding mechanism, and reciprocating means for transferring the topmost blank from the patch applying mechanism to the gumming and folding mechanisms.
3. In an envelop machine, means for supporting a pile of envelop blanks having openings therein, means for applying a patch to cover an opening in the topmost blank in said pile, reciprocating means for transferring the patched blank from the pile of blanks to a gumming mechanism for gumming the flaps, means for applying adhesive material to the flaps of the blank, a folding mechanism, and reciprocating means for transferring the gummed blank to the folding mechanism.
4. In an envelop machine, the combination with flap gumming and flap folding mechanisms and means for transferring an envelop blank from the flap gumming mechanism to the flap folding mechanism, of means for applying a patch to the envelop blank to cover an opening therein, said transferring means being adapted to move the blank from the patch applying mechanism to the flap gumming mechanism.
5. In an envelop machine, a support for an envelop blank having an opening therein, means for applying gum to a transparent strip, means for severing the strip to form an individual patch, means for applying the gummed patch to cover the opening in the envelop blank, means for gumming the flaps of the blank, means for folding the blank, and means for transferring the blank from the patch applying mechanism to the gumming and folding mechanisms successively.
6. In an envelop machine, a support for a pile of envelop blanks having openings therein, means for applying a transparent patch to cover the opening in the topmost blank of the pile, means for moving the topmost blank from the pile of blanks, a supporting table for individual blanks as they are successively moved from the pile, and means for applying adhesive material to the flaps of the blank as it is supported on said table.
7. In an envelop machine, mechanism for applying a patch to an envelop blank, mechanism for folding the blank, reciprocating means for transferring the blank from the patch applying mechanism to the folding
- mechanism with an intervening dwell, and reciprocating mechanism for applying adhesive material to the flaps of the blank during said dwell.
8. In an envelop machine, a stationary support for an envelop blank having an opening therein, means for applying a patch to a blank held on said support to cover said opening, a folding mechanism, means for transferring a blank by a step by step movement from said support to said folding mechanism, and means for applying adhesive material to the flaps of the blank between the steps of said transferring mechanism.
9. In an envelop machine, a support for a pile of envelop blanks having openings therein, means for applying a patch to cover the opening in the topmost blank in the pile of blanks, means for raising the topmost blank from the pile of blanks, means for moving the raised blank from the pile of blanks to a folding mechanism with an intervening dwell, means for applying adhesive material to the flaps of the blank during said intervening dwell, and a flap folding mechanism.
10. In an envelop machine, means for supporting a pile of blanks having openings therein, means for feeding the end of a continuous strip into a position over the opening in the topmost blank, means for severing the continuous strip, means for applying the severed piece to cover the opening in the topmost blank, means for raising the topmost blank, means for moving the raised blank from the pile of blanks to a folding mechanism with an intervening period of dwell, means for applying adhesive material to the flaps of said blank during its period of dwell, and means for folding the blank.
11. In an envelop machine, a support for a blank having an opening therein, a support for a continuous coil of transparent paper, means for withdrawing the transparent paper from the coil in predetermined lengths, means for applying adhesive material to the transparent paper at predetermined intervals, means for severing the transparent paper, means for applying the severed piece to cover the opening in the blank, a suction tube for raising the blank, means for moving the raised blank to a gumming mechanism, and a gumming mechanism for applying adhesive material to the flaps of the blank.

Dated this ninth day of February, 1916.
